UNITED STATES PATENT OFFICE.

ADOLPH SHOENINGER, OF CHICAGO, ILLINOIS.

DESIGN FOR CHILDREN'S CARRIAGE.

Specification forming part of Design No. **7,601**, dated July 28, 1874; application filed May 5, 1874.
[Term of Patent 3½ years.]

To all whom it may concern:

Be it known that I, ADOLPH SHOENINGER, of Chicago, in the county of Cook and State of Illinois, have invented a Design for a Baby-Carriage, of which the following is a specification:

The nature of my design is fully represented in the accompanying photographic illustrations, to which reference is made, and in which—

Figure 1 is a perspective view of the carriage; and Fig. 2 is a similar view of its running gear, the wheels and body being removed.

A A represent the axles and reach B, Fig. 2, composed of iron segments welded together. C, Fig. 2, is my peculiar combination of

springs and perches, which combination of parts, in the form shown, affords a light and elegant design.

What I claim as my invention is—

1. The design for the peculiar combination of springs and perches for a baby-carriage, constructed substantially as described and shown.

2. The design for a baby-carriage, consisting of the axles, the wheels, the combination of springs and perches C B, body D, and canopy, substantially as shown.

ADOLPH SHOENINGER.
